UNITED STATES PATENT OFFICE.

HUBERT KRESS, OF FRANKFORT-ON-THE-MAIN, GERMANY.

HIGH-TENSION TRANSFORMER.

Application filed April 9, 1923. Serial No. 630,915.

To all whom it may concern:

Be it known that I, HUBERT KRESS, a citizen of Germany, residing at Frankfort-on-the-Main, Germany, have invented certain new and useful Improvements in High-Tension Transformers, of which the following is a specification.

This invention is an improvement in high tension transformers of that kind in which the transmission of energy from the generator or the like to the high tension windings or secondary coils or conversely is effected by one or more intermediate links suitable for transmission of electro-magnetic energy, such as transformers, condensers or the like, which can maintain a definite potential given to them.

According to the present invention the energy transmitting link is constituted by the iron core of the transformer itself, which is strongly insulated from the low tension or exciting winding and from the earth. The high tension winding is subdivided into two electrically connected sections between which the exciting winding is arranged on and strongly insulated from, the iron core which is controlled as regards its potential and insulated from the earth. This results in a simpler construction and in considerable economies in material.

Three different constructions according to the invention are illustrated by way of example in the accompanying drawing.

Figure 1 shows a transformer for, say, 200 kilovolt secondary tension.

Figure 2 shows a transformer for say 200 kilovolt in which however the arrangement of the windings is slightly different from that shown in Figure 1.

Figure 3 shows a transformer in which in front of the high tension transformer a help-transformer is connected.

The left hand side of each figure gives the connection diagram, whilst the right hand side shows more fully the construction. The invention is embodied in each half of the figures, so that either the right or the left hand side can be omitted.

In all the three constructions (Figures 1-3), the high tension winding is subdivided into two parts *a* and *b*. The exciting winding *d* is arranged between them on an open or closed iron core *c*. The iron core is insulated from the earth, this being done

for instance by insulators *m* supporting the casing *l*.

If in the connection according to Figure 1 the potential difference between the secondary terminals *x*, *y* of the transformer, which is earthed at *e* be 200 kilovolts, the potential values at various points of the transformer will be those given in the unbracketed figures. A potential of 50 kilovolts is given to the iron core by the connection *n*. The potential differences between the important points of the high tension windings *a*, *b*, iron core *c* or casing *l* and the exciting winding *d* are given in brackets. It will be seen that the potential difference at no point exceeds 50 kilovolts.

In Figure 1 the two central turns *f* and *h* of the high tension windings *a* *b* are to be insulated from the low tension winding *d*, because there is a potential difference of 50 kilovolts between them. In the construction of Figure 2 in the contrary only one end *f* of the winding *a* needs to be insulated from the exciting winding *d*. This is made possible by placing the initial point *h* of the high tension winding between the two windings *a* and *b*, close to the exciting winding *d*. The outer end *g* of the winding *b* is electrically connected to the inner end *f* of the winding *a* by the conductor *g* or preferably by means of the iron core. The potential at the central turn *h* of the winding *b* will then be zero, so that this end can be connected to the exciting winding *d*, and need not to be insulated from it. The winding *d* can therefore be brought close to the end *h* of the winding *b*, so that insulation at that point will not be necessary.

The transformer in Figure 3 which is built say for 300 kilovolts, is in its upper part *a* *b* *c* *d*, a transformer according to Figure 2. The exciting winding *d* is not however supplied directly from a line circuit or generator or the like, but receives its energy from a winding *d'* arranged over an iron core *c'* between the two windings *a'* *b'* of a help-transformer, the core *c'* of which is excited by a winding *p*. The winding *d'* generates in a few turns of a thick wire a low tension current which excites the coil *d*. Owing to the connection to the inner ends of the windings *a'* and *b*, a higher potential (50 kilovolts) is superposed over the low tension of the exciter windings *d* *d'*,

Also in the construction in Figure 3, the potential difference is nowhere higher than 50 kilovolts.

What I claim is:

- 5 1. A high tension transformer having a high tension winding, an exciting winding and an iron core, said high tension winding being divided into two electrically connected sections, said exciting winding being arranged between said sections and highly insulated from said core, and said core being insulated from earth and given a predetermined potential with respect thereto.
- 10 2. A high tension transformer including a high tension winding divided into two spaced electrically connected sections, an iron core insulated from earth and having a predetermined potential in respect thereto, an exciting winding arranged between the said sections and highly insulated from said core, one end of said high tension winding being at ground potential, situated between the said sections and adjacent said exciting winding whereby no insulation is required
- 15 20 25 between said exciting winding and one section of said high tension winding.
3. A high tension transformer including

a high tension winding divided into two spaced sections, an iron core insulated from earth and having a predetermined potential with respect thereto, an exciting winding arranged between said sections and highly insulated from said core, one end of said high tension winding being at zero potential and adjacent said exciting winding, and the two sections of said high tension winding being connected through said core.

4. A high tension transformer including a high tension winding divided into two electrically connected sections, an iron core insulated from earth and having a predetermined potential with respect thereto, an exciting winding, highly insulated from said core, arranged between said sections, one end of said high tension winding being given a zero potential arranged adjacent and connected to said exciting winding.

In testimony whereof I affix my signature in presence of two witnesses.

HUBERT KRESS.
